UNITED STATES PATENT OFFICE.

MARTIN F. WITT, OF LOS ANGELES, CALIFORNIA.

MEANS FOR BURNING CRUDE OIL.

Application filed January 27, 1921. Serial No. 440,323.

To all whom it may concern:

Be it known that I, MARTIN F. WITT, a citizen of the United States, residing at Los Angeles, in the county of Los Angeles and 5 State of California, have discovered and invented new and useful Improvements in the Means for Burning Crude Oil, of which the following is a specification.

This invention relates to a new and useful 10 method of and means for burning crude oil in which an expansive medium as steam or air under pressure is employed to spray or vaporize the oil before its introduction into a furnace; and an object of the invention is 15 to provide a burner of this character which will be superior in operation and can be satisfactorily used with crude oil having an asphaltic base that is liable to clog and gum up the burner.

20 The invention also relates to improvements by which the burner can be instantly cleansed with great ease and practically without interruption of the fire in the furnace.

I have discovered that the operation of 25 burning crude oil is improved by dividing the oil by forcing it through very fine perforations; and I prefer to use perforations of from $\frac{1}{16}$ to $\frac{3}{32}$ of an inch in diameter; but do not limit myself to perforations of 30 this size, nor to either circular, angular or slot forms of perforations; but may use perforations of any desired and convenient form narrow enough to be effective.

An object of the invention is to cause a 35 high rate of combustion and to produce a white flame with crude oil.

An object of the invention is to provide a crude oil burner of this character which can be instantly cleansed or automatically 40 blown out so as to clear away any deposits occurring in the burner, and to put the burner into condition for perfect action by simple movements of a lever.

45 My invention and discovery includes, first fluidifying the liquid fuel under heat and pressure; then finely dividing the fuel with a hot expansive medium as steam, then mixing such medium and finely divided fuel, and immediately expanding the mixture and 50 introducing it at once into the furnace or other place of combustion and there igniting it.

I provide a pressure chamber and an expansion chamber and interpose a perforated 55 plate between such chambers so that the fluid fuel is finely divided by action of and by

mixing with the expansive medium, and is at once blown from such expansion chamber into the combustion chamber or fire box of a furnace where it is ignited and burned. 60

I provide means by which the expansive medium can be applied to cleanse the perforations in the perforated plate as desired. The burner is provided with a normally 65 closed blow-out.

I have provided a burner in which the oil and steam is first brought together in a pressure chamber where the oil is subjected to both heat and pressure so as to make its constituents more highly fluid, and then the 70 oil is blown through means for finely dividing the oil; after which expansion and mixing is effected, and then the mixture, in the form of a fine vapor, is ejected from the burner into the furnace and is at once combusted so that there is no return of any part thereof to liquid state. 75

A principle of this invention is the arrangement within an expansion and mixing chamber having an outlet for the mixture of fuel and air or steam; of means for spraying the fuel into such expansion and mixing chamber in a highly divided state, and means whereby the fuel breaking up 80 device used to spray the fuel into the expansion chamber, can be subjected to a blast of the expansive fuel-projecting medium, either steam or air as the case may be, sufficient to remove all deposits from the burner at a 85 moment's notice. 90

An object of the invention is to so construct the blowing out contrivance that when it is put into operation, the obstructions, if any, which have occurred in the burner, will 95 be blown out irrespective of the character or size of the accumulations that may form; and to this end I supply a passage of appropriate size to allow such obstructions to pass, and arrange for closing said passage by a suitable valve or a plug when the burner 100 is in normal operating condition.

An object is to make provision for great range of heating capacity combined with economy of fuel, and to regulate the heat from a very low fire to a fire of great volume. 105

Other objects, advantages and features of invention may appear from the accompanying drawings, the subjoined detail description and the appended claims.

The invention may be carried out in numerous ways with apparatus of different forms, and the accompanying drawings illustrate 110

- some of the forms in which I have embodied, and in which I contemplate embodying my newly invented apparatus and putting my invention and discovery into practical use.
- 5 Figure 1 is an elevation of one form of my newly invented oil burner installed in a steam boiler furnace, a fragment of which is shown.
- 10 Fig. 2 is an enlarged fragmental detail of the control.
- Fig. 3 is a fragmental axial section on line x^3 , Fig. 4, of a simple form of the burner.
- 15 Fig. 4 is a plan section on line x^4 , Fig. 3.
- Fig. 5 is an enlarged section of the burner on line indicated at x^5 , Figs. 1 and 6.
- 20 Fig. 6 is an elevation in section on line x^6 , Fig. 5.
- Fig. 7 is a fragmental view of the burner shown in Figs. 1, 5 and 6, with the valve open for the purpose of cleansing the burner.
- 25 Fig. 8 is a vertical axial section of another form of burner embodying the invention with a crank-actuated valve, and showing the parts in cleansing position.
- Fig. 9 is a plan section on line indicated at x^9 , Figs. 8 and 10.
- 30 Fig. 10 is an elevation in section on line x^{10} , Figs. 8 and 9.
- Fig. 11 is an enlarged elevation of the valve shown in Figs. 8, 9 and 10.
- Fig. 12 is a plan of the valve in section on line x^{12} , Fig. 11.
- 35 Fig. 13 is a fragmental axial sectional elevation of another form of crank-actuated valve.
- Fig. 14 is an axial section of a burner constructed in accordance with this invention with a shearing valve.
- 40 Fig. 15 is a plan section on line x^{15} , Fig. 14.
- Fig. 16 is a sectional elevation on another form of the burner constructed with a reciprocating valve.
- 45 Fig. 17 is a section on line x^{17} , Fig. 16.
- Fig. 18 is an axial section of a burner constructed in accordance with this invention and provided with a reciprocating expansion valve adapted to automatically operate through the action of steam pressure, and valve closing means, which is shown in this view as a weighted lever arranged to allow the valve to blow off after the manner of a safety valve.
- 50 Fig. 19 is a plan section on line x^{19} , Fig. 18.
- Figs. 20, 21, 22, 23 and 24 are views of another form of the burner. The blowing out is here effected by means of valves having an oscillating, shearing, or slide motion. The burner is here shown without any expansion chamber beyond the blow-out; it being understood that the mixing and expanding in this case occurs in the burner or
- 55 fire box of the furnace.
- Fig. 25 is a top plan view of another form of the burner and its control.
- Fig. 26 is an enlarged sectional elevation on line x^{26} , Fig. 25 looking in the direction of the arrow.
- 70 Fig. 27 is a section on line x^{27} , Fig. 25, looking toward the right.
- Fig. 28 is an enlarged plan view of the lower portion of the burner shown in Figs. 26 and 27, the expansion chamber being removed in part to expose the edge of the perforated plate which constitutes the fuel dividing means of the furnace.
- Fig. 29 is a view of another form of the burner installed in the furnace, a fragment of which is shown.
- Fig. 30 is a fragmental longitudinal section of what is shown in Fig. 29.
- Fig. 31 is a fragmental detail of the construction of the burner shown in Figs. 29 and 30.
- In the drawings, like parts are indicated by like characters and various forms of those elements having practically the same function are indicated by like letters with an addition of an Arabic numeral to mark the distinction where the forms are different with little if any variation of function.
- Referring first to the form shown in Figs. 1, 2, 5, 6 and 7, the oil burner body a is constructed with a compression chamber b , an expansion chamber c provided at right angles thereto with the mixture outlet d , a by-pass-valve chamber e and mixing means f normally separating between the compression chamber b and the expansion chamber c when the valve g is closed. h is a steam pipe surrounding an oil pipe i . These two pipes discharge into the compression chamber through the inlet j .
- 90 Referring first to the form shown in Figs. 1, 2, 5, 6 and 7, the oil burner body a is constructed with a compression chamber b , an expansion chamber c provided at right angles thereto with the mixture outlet d , a by-pass-valve chamber e and mixing means f normally separating between the compression chamber b and the expansion chamber c when the valve g is closed. h is a steam pipe surrounding an oil pipe i . These two pipes discharge into the compression chamber through the inlet j .
- 95 The valve chamber e is closed by a suitable gland k around the valve rod m .
- The body a is preferably of cast steel and the oil dividing and mixing means inside the body is shown as a semi-tempering steel disk f having fine perforations n therethrough.
- 100 The mixture outlet d is provided with inwardly extending lips o , p , to deflect the mixture so as to produce a higher circulation of the mixture in the expansion and mixing chamber c , thus to intimately mix the fuel and expansive medium before it issues from the burner.
- 105 The pressure on the oil in pipe i may be from 40 to 60 pounds per square inch, so that the burner will operate against such a pressure of steam. The oil is pumped by pump P into oil pressure tank T , from which it is delivered to the burner B by oil pipe A having a check valve R to prevent back flow of oil.
- 110 The oil pressure is set at a predetermined amount depending upon the pressure of steam to be carried. As the steam pres-

sure rises; the oil will be retarded; and vice versa. The steam pressure picks up the oil in the pressure chamber and drives it through the restricted outlet formed by 5 the finely perforated fuel dividing plate or element *f*.

The steam being admitted to steam pipe *h* will carry the oil from the compression chamber *b* through the perforated disk *f* 10 into the expansion and mixing chamber. Said expansion chamber is of considerable length or height as compared with its diameter; being shown in the drawings about twice as long as it is wide, so that the fuel 15 and steam will have ample room for expanding and mixing before the mixture reaches the outlet *d* which is intermediate the ends of said expansion-and-mixing chamber. The outlet is located intermediate the ends of the 20 expansion and mixing chamber and is shown as standing at about $\frac{1}{3}$ of the way from the divider and mixer *f* to the upper end of the expansion-and-mixing chamber. By locating the outlet at this point, a satisfactory 25 mixture is delivered through the outlet *d*.

In practical operation of the form shown in Figs. 1, 2, 5, 6, 7, the valve *g* will be closed as shown in Figs. 5 and 6, so that the oil and steam will pass freely through the perforations *n* in the disk *f*. The oil and steam expand from the perforations *n* into the expansion and mixing chamber *c*, and the steam pressure, co-acting with the finely perforated plate *f*, causes a thorough breaking 30 up of the oil, and a thorough mixing of the same with the steam before the fuel issues at *d* where it will be ignited.

The valve *g* is shown as having a concave face presented to the compression and expansion chambers *j*, *c*. Said valve fits the valve chamber *e*, and against the edge of the mixing plate *f*, and prevents the passage of steam and oil around said plate while the valve is closed. The valve chamber *e* permits the valve *g* to be withdrawn from the disk *f*, and when this is done the steam rushes along both sides of the disk, scouring the under side of the disk with action toward the valve, and the upper side with action away from the valve. Meanwhile steam pressure is operating to blow out any accumulations within the perforations as the clogging material is weakened by the removal of portions thereof from the opposite 55 sides of the disk.

The upper end of the mixing chamber *c* is of conical form as at 9 at the axis of the burner opposite the dividing element *p* so that the reverberation of the fuel and expansive medium in chamber *c* will be largely balanced thereby; thus obtaining more perfect results in the mixing and the discharge 60 of the mixture from the chamber *c* through the mixture outlet *d*.

65 In Fig. 8, the finely perforated breaking

up or mixing plate *f* has a blow-out way *e*¹ closed by a crank operated valve *g*¹. The plate *f*¹ is concave on the under side and is finely perforated, so that when the valve is closed the fuel and expansive medium issue 70 through the fine perforations, and when the valve is opened as shown in said Fig. 8, the great rush of steam on the concave under side of the plate tends to break up the accumulations if any, on the plate, and carries the same out at the way *e*¹. This operation may be effected while the oil is turned on, or the oil may be cut off by the oil valve such as *r* in Fig. 1. 75

There are fine grooves or corrugations *s*, 80 between the conical tip *t* of valve *g*¹ and the rim of the blow-out way *e*¹, so that when the valve is closed, there will be fine passages for the fuel, between the tip and the rim of the blow-out passage. 85

These fine passages formed by the grooves at *s* cooperate with the perforations *n* in the concavo-convex plate *e*¹.

The valve *g*¹ has a laterally elongated bearing *u* for the crank pin *v*, and the 90 valve *g*¹ operates in the guide *w*.

In Fig. 13 the reciprocating valve comprises a body *g*² having conical tips *t*¹ to enter the holes *n*. The valve rod *m* is provided with a crank pin *v* operating in the 95 bearing *u*.

In Fig. 14 the perforated slide valve *g*² slides on the perforated disk *c*² and is operable by the valve rod *m*² working through the stuffing box *k*². The steam pipe *h* is 100 provided at its front end by deflectors *y* and *z* to assist in the mixing. The slide valve *g*² has perforations 2 therethrough to cooperate with the perforations *n*².

In the form shown in Figs. 16 and 17, the reciprocating valve *g*³ closes a large port *n*³. The reciprocating valve rod *m*³ operates the valve *g*³ and is in turn closed by the weighted lever 4 after the manner of a safety valve. 105

In Figs. 18 and 19, the valve rod *m*⁴ operates the valve *g*⁴. The baffle 5 directs the fuel mixture up into the circular mixing chamber *c*. 110

In Figs. 20, 21, 22, 23, and 24 a sleeve 6 is mounted to revolve in a hollow nozzle 7 which is tapered and is provided with various sized orifices 8.

When this device is used the orifices 8 and 9 are brought more or less into register 115 by revolving the sleeve in on the nozzle.

The nozzle is closed at the end so that the supply from the outlets is driven radially from the axis of the burner into the boiler.

In Figs. 25, 26, 27, and 28 the burner body *a*² is of an elliptical form in plane and it is composed of upper and lower sections 10 and 11, which are clamped together by screws 12 and are provided with a seat 125 for the fuel divider *f*⁴. The widely ex- 130

tended outlet d^4 in one long side of this burner is provided for making a wide flame.

In Figs. 29 and 30 a valve g^5 inside a steam pipe h^5 is provided with perforations n^5 and is operable in the nozzle 15 which is provided with lateral outlets n^5 . When moved toward the inlet to the nozzle the outlets n^5 are successively closed and open vice versa when the valve is moved in the opposite direction outside of the nozzle, and there is arranged an expansion chamber e^5 which is in the form of a skirt converging to a collar 16, that is screwed or otherwise secured to the steam pipe h^5 .

The oil pipe i preferably terminates short of the perforations n^5 .

It is understood that the blow-off for cleaning out the burner may be arranged in different ways, and in Fig. 28 a blow-off valve 17 is provided for that purpose.

In starting the burner into operation it is first necessary to get some steam pressure. Fire of wood or other fuel may be put into the coal furnace in order to get a steam pressure for starting. When the pressure has been raised to fifteen or twenty pounds then the burner may be started into successive operation by turning on the steam full heat, and the oil according to the requirements. When the steam has reached the preferred pressure of from forty to sixty pounds the valve will be set to produce the best results.

In case any clogging occurs the fuel may be shut off and full steam pressure turned on, thus blowing out the accumulations as above indicated.

In the form shown in Figs. 3 and 4 no provision is especially made for automatically removing accumulations from the divider f^6 which is cast integral with the body a^6 . The lower end of the burner is threaded to receive a blow-out plug 18 which may be unscrewed from time to time to allow the blowing-out operation to be performed. This also gives direct access to the divider.

In the forms shown in Figs. 6, 7, 8, 10, 13 and 14 the divider is inserted into a seat 19 and is secured in there by a hollow bushing 20 of suitable construction to form the interior of the compression chamber.

In the form shown in Fig. 18 a plug 21 in the burner body a^4 admits the valve g^4 and carries the valve rod gland h^4 .

In Fig. 10 the burner body a^{10} is threaded at both ends to receive the plugs 22 and 23. The plug 23 on the expansion side is provided with a mixture outlet d^{10} so that the burner may be supplied with two such outlets.

In the form of burner shown in Figs. 5, 6 and 7 the valve chamber or way e practically fits the valve excepting for the by-

pass inlet 24 which allows the valve to be opened. The concave middle of the valve fits against the disk when the valve is closed. The various steam and oil valves are operable by a lever 25 or by any other suitable means, and said lever is shown as being held in the operable position by a spring 26 acting against a stationary abutment 27, and operating through rod 28 to pull the lever 25 into operating position.

It is understood that the frictional obstruction at the fuel dividing exit formed by the perforated plate f may be variously constructed without departing from the spirit of the invention and that other changes may be made. The main principle of the invention being that flow-obstructing and fuel-dividing means, as the plate f between the inlet at j to the burner and the outlet at d from the burner, shall be such as to effect the desired mixing, and the valve as at g and the various equivalents thereof shown is adapted to direct the expansive medium angularly relative to the fuel dividing means so as to cleanse the same when the valve is opened.

I claim.

1. An oil burner having a compression chamber; means for supplying liquid fuel and an expansive medium to the compression chamber; a fuel dividing exit for the fuel and expansive medium during normal operation of the burner; and a valve-controlled exit from the compression chamber; the parts being arranged to direct the flow of expansive medium to remove obstructions from the top and bottom surfaces of the fuel dividing exit when the valve-controlled exit is opened.

2. The oil burning apparatus set forth comprising a hollow body provided with an inlet at one end and an outlet intermediate the inlet and the other end; flow obstructing and fuel dividing means between the inlet and the outlet; said dividing means separating the cavity of the hollow body into a compression chamber and an expansion chamber; there being a passage from the compression chamber to the expansion chamber and a valve to close and open said passage for the purpose of blowing out accumulations which may occur in the compression chamber.

3. An oil burner comprising a compression chamber into which liquid fuel and an expansive medium under pressure is introduced; an expansion and mixing chamber having an outlet from which the mixture issues; fuel dividing means between the chambers to allow fuel and expansive medium to pass in finely divided form from the compression chamber to the expansion chamber; and means for opening an enlarged passage from the compression chamber for the purpose of directing the ex-

pansive medium angularly relative to the fuel dividing means so as to cleanse the same to allow normal operation when the valve is again closed.

5. 4. An oil burner comprising a pressure chamber, an expansion chamber, provided with an outlet for fuel; a perforated plate between said chambers; means to supply the pressure chamber with fuel and expansive medium; a fuel passage from the compression chamber to the expansion chamber; and means to open said passage to allow a rush of expansive medium to cleanse the plate and to close said passage for normal operation.

5. The oil burning apparatus set forth comprising a hollow body provided with an inlet at one end and an outlet intermediate the inlet and the other end; flow obstructing and fuel dividing means between the inlet and the outlet; said dividing means separating the cavity of the hollow body into a compression chamber and an expansion chamber; there being a passage from the compression chamber to the expansion chamber around said dividing means and a valve to close and open said passage for the purpose of blowing out accumulations which may occur in the compression chamber.

30. 6. An oil burner comprising a compres-

sion chamber into which liquid fuel and expansive medium under pressure is introduced, an expansion and mixing chamber having an outlet at right angles to the body of said burner from which the mixture issues, a perforated plate interposed between said chambers, a fuel passage from the compression chamber to the expansion chamber, and means to open said passage to allow a 40 rush of expansive medium to cleanse the plate and to close said passage for normal operation.

7. An oil burner adapted to use an expansive medium and having a chamber in which oil and steam are applied under pressure; means for finely dividing the oil and allowing it and the expansive medium to issue from the chamber; and means whereby the expansive medium is directed angularly in said chamber relative to the fuel dividing means, whereby accumulations in said chamber may be blown out at intervals by the angularly directed expansive medium.

In testimony whereof, I have hereunto set my hand at Los Angeles, California, this 13th day of January, 1921.

MARTIN F. WITT.
